US0D1085600S

(12) United States Design Patent (10) Patent No.: US D1,085,600 S
(45) Date of Patent:  Jul. 22, 2025

(54) STAND FOR CLEANER

(71) Applicant: Samsung Electronics Co., Ltd., Suwon-si (KR)

(72) Inventors: Sanghoon Yoon, Suwon-si (KR); Jinsun Park, Suwon-si (KR); Hwandong Lee, Suwon-si (KR); Jaewon Choi, Suwon-si (KR)

(73) Assignee: Samsung Electronics Co., Ltd., Suwon-si (KR)

() Term: 15 Years

(21) Appl. No.: 29/810,098

(22) Filed: Oct. 1, 2021

(30) Foreign Application Priority Data

Apr. 21, 2021 (KR) 30-2021-0019351

(51) LOC (15) Cl. 15-05

(52) U.S. Cl.

USPC D32/31

(58) Field of Classification Search

(57) CLAIM

The ornamental design for a stand for cleaner, as shown and described.

DESCRIPTION

FIG. 1 is a front perspective view of a stand for cleaner showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a front perspective view of the stand for cleaner in which a cleaner is provided in broken lines to illustrate an example environment.

The broken lines in the figures depict portions of the stand for cleaner which form no part of the claimed design.

The broken lines illustrating the cleaner feature in FIG. 8 depict environmental subject matter and form no part of the claimed design.

1 Claim, 8 Drawing Sheets
